UNITED STATES PATENT OFFICE.

WILLIAM DODGE HORNE, OF YONKERS, NEW YORK.

PROCESS FOR DEFECATING SUGAR JUICE

No Drawing.

Application filed November 13, 1919. Serial No. 337,828.

To all whom it may concern:
 Be it known that I, WILLIAM Dodge HORNE, a citizen of the United States, and a resident of the city of Yonkers, county of 5 Westchester, and State of New York, have invented a new and Improved Process for Defecating Sugar Juice, of which the following is a full, clear, and exact description.

This invention relates to a process for the 10 defecating of sugar juice and has reference more particularly to a process of the class described, in which the sugar juice is first treated with lime to strong alkalinity to litmus and after the removal of the precipitate formed, a precipitant such as sodium phosphate is added to precipitate the excess of lime.

A complete precipitation of the precipitable impurities in cane juice can only be 20 attained by adding lime considerably beyond the point of a slight alkalinity to litmus, but it is not always necessary to add lime to the point of alkalinity to phenolphthalein. The exact amount may be determined by experiment by testing the filtrate from any particular lime addition with more lime and heating to see if a further precipitate is thrown down. In the case of burnt, fermented or unusually acid sugar 30 juice, soda, such as the hydroxide, carbonate or bicarbonate of sodium, may be added to make the precipitation more complete. Only a moderate heat, 105-150 degrees F., is necessary to complete the precipitation. Deficiency of lime cannot be made up for by 35 excessive heating. The practice heretofore has been to heat the sugar solution to 200° F. or over, after adding a quantity of lime which would not destroy the invert sugar at the high temperature. However, this quantity is insufficient to precipitate all the impurities in the sugar solution. In any event 40 the solution must be strongly alkaline to litmus to insure the insolubility of the precipitate formed.

Any appreciable amount of lime left in a sugar solution is very detrimental, as in the heating of the solution to evaporate and crystallize, the lime combines chemically 45 with the reducing sugars, forming dark col-

ored bodies which cannot be removed by crystallization, but remain in solution and prevent the crystallization of large amounts of sugar. Therefore in any satisfactory 55 method of defecation some means must be provided for removing that portion of the added lime which is not precipitated by the acids, gummy substances, nitrogenous bodies, etc., in the raw juice. If the excess of lime over that existing in the precipitate 60 be neutralized with phosphoric acid alone or a phosphate acid to litmus in the presence of the precipitate, the precipitate will immediately redissolve in large part, allowing the once separated impurities again to enter into solution and so defeat the object of 65 the defecation.

The object of this invention therefore is to filter, settle out, or float off the precipitated impurities, resulting from the addition of lime, from the clarified juice, and then to remove the excess of lime so as to prevent the subsequent destruction of reducing sugars, formation of dark colored melanogenic substances, formation of lime scales 70 on the heating tubes and surfaces of the heating appliances, slow boiling, cloudy residual molasses, and a strong disagreeable taste in the final sugar products.

The removal of the excess of lime is best 75 accomplished by the addition of sufficient suitable lime precipitant, such as a soluble phosphate, carbonate, bicarbonate, sulphite, bisulphite, oxalate, etc., preferably neutral or slightly alkaline to litmus, at a temperature of 175° F. or above. Phosphoric acid alone or a phosphate acid to litmus alone is not suitable for this purpose, as such reagent is far from thorough in its removal 80 of lime. However, said phosphoric acid or acid phosphate may be mixed with the proper proportion of the oxide, hydrate, carbonate, and (or) bicarbonate of sodium; and on adding this mixture to the sugar-containing liquid, the lime is practically 85 thoroughly precipitated. The more basic soluble phosphate, etc., is far more efficient in its lime removing power than phosphoric acid or a phosphate acid to litmus. A soluble phosphate of soda may be used to pre- 90

50 55 60 65 70 75 80 85 90 95 100

cipitate the excess lime, and very good results are obtained thereby. Such a soluble phosphate or equivalent is added in correct proportion, determined or checked, by experiment, and the solution is then heated to near the boiling point with safety, as neither sugar nor reducing sugar is destroyed nor attacked, but the lime is almost completely precipitated immediately as an insoluble phosphate or other compound. The separate ingredients for forming any of these precipitants may be added separately to the juice with equally good effect. The resulting precipitate settles very quickly in the solution, leaving it bright and clear as well as very light colored and suitable for making the very best grade of raw sugar or even a sugar for direct consumption. This second precipitation, with a phosphate neutral or alkaline to litmus, further removes the iron from the juice, which greatly improves the latter for making either direct consumption sugars or raw sugars for refining. It removes also the small pieces of cane fibre or bagasillo which escape the first effort at clarification and which if left in the juice find their way into the raw sugar, where they retain their moisture and become centers of infection by micro-organisms which ferment the sugar and cause large deterioration losses in storage and transportation.

The precipitation with the lime and with the phosphate can be easily carried out without any special machinery or appliances as the sedimentations may take place in ordinary tanks.

The two precipitates, settled from their respective solutions, after once diluting and decanting, may be combined and filter-pressed. The press cake may be used as an efficient fertilizer as it contains practically all of the nitrogenous matter of the raw juice and all the phosphatic matter of the defecant. This phosphatic matter, further, is nearly all in the form immediately available to plants as food, and the little that may not be immediately available will gradually become available in the soil.

To the fresh cold cane juice, milk of lime or dry lime is added to beyond the point of alkalinity to litmus and sufficient to precipitate completely all those substances precipitable by lime. This will be about .030% or .040% lime on the weight of the juice. An average juice is acid and requires .02% lime to neutralize to litmus and .04% lime to neutralize to phenol phthalein. It will require about .03% to .04% lime to precipitate fully all the precipitable matters. This limed juice is heated in Louisiana to about 105° F. to effect complete precipitation; in Porto Rico to about 150° F. At these moderate temperatures no invert sugar is destroyed. The juice is settled and the clear

juice decanted or the juice is filtered. To the clear juice is now added about .02% of actual acid calcium phosphate and enough sodium carbonate to insure a neutral or approximately neutral reaction to litmus in the sugar solution. Part of the acid phosphate precipitates the free lime and the remainder reacts with the sodium carbonate to produce phosphate of soda, which immediately combines with the lime of the dissolved lime salts in the solution, precipitating this lime. The amount of this sodium carbonate is about one-third of the acid phosphate used. Phosphoric acid can be used as a substitute for acid phosphate of lime; so also may one employ phosphate of soda directly instead of forming it in the sugar solution. After adding these re-agents the temperature is raised to about 200° F., and the precipitate then formed is settled out, leaving a light colored solution freer than usual from organic matters and free from uncombined lime and almost free from combined lime.

I would state in conclusion that while the process described constitutes a practical embodiment of my invention, I do not limit myself strictly to the details herein described, since manifestly the same can be considerably varied without departure from the spirit of the invention as defined in the appended claims.

Having thus described my invention, I claim as new and desire to secure by Letters Patent:—

1. A process for defecating sugar containing liquids which consists in adding to said liquids sufficient lime to give a complete precipitation of all substances precipitable by lime and to impart a strong alkalinity to the sugar containing liquid, maintaining said liquid at a temperature ranging from 105° F. to 150° F., separating the precipitate, subjecting the solution of strong alkalinity to the action of a mixture of phosphoric acid and sodium carbonate to precipitate both the free lime and the lime contained therein in the form of dissolved lime salts, and then raising the temperature of the liquid to a point above 150° F. to facilitate the last mentioned reactions.

2. A process for defecating sugar containing liquid which consists in adding to said liquid sufficient lime to give a complete precipitation of all substances precipitable by lime and leave the liquid in a state of strong alkalinity, maintaining said liquid at a degree of temperature between 105 F. and 150 F., and separating the precipitate, subjecting the solution of strong alkalinity to the action of a mixture of an acid phosphate and a sodium salt to precipitate both the free lime and the lime remaining in the liquid in the form of dissolved lime salts, the last mentioned reaction being carried out at a degree of temperature in excess of 150 F.

3. A process for defecating sugar containing liquids which comprises adding to said liquid .03% to .04% of lime to cause precipitation of matter in the liquid and impart 5 a strong alkalinity to the sugar containing liquid, separating the precipitate, subjecting the solution of strong alkalinity to the ac-

tion of a mixture of phosphoric acid and sodium carbonate to precipitate the free lime in solution and the lime contained in 10 said solution in the form of dissolved lime salts, and raising the temperature of the solution in excess of 150 F.

WILLIAM DODGE HORNE.
